(57) CLAIM

We claim the ornamental design for an accessory hanger, as shown and described.

DESCRIPTION

FIG. 1 is a perspective view of an accessory hanger;
FIG. 2 is a front view of an accessory hanger;
FIG. 3 is a rear view of an accessory hanger;
FIG. 4 is a side view of an accessory hanger;
FIG. 5 is a bottom view of an accessory hanger; and,
FIG. 6 is a top view of an accessory hanger.
The broken lines showing in the drawings illustrate the general environment in which the claimed design is utilized.
